(57) **CLAIM**

We claim, the ornamental design for an earphone-type electronic device with display, as shown and described.

DESCRIPTION

FIG. 1 is a perspective view of an earphone-type electronic device with display showing our new design;
FIG. 2 is a front elevation view thereof;
FIG. 3 is a rear elevation view thereof;
FIG. 4 is a left-side elevation view thereof;
FIG. 5 is a right-side elevation view thereof;
FIG. 6 is a top plan view thereof;
FIG. 7 is a bottom plan view thereof;
FIG. 8 is a perspective view thereof, shown the article in use; and,
FIG. 9 is a partial view thereof, shown in folded position. The broken lines indicating human figure is for illustrative purpose only and form no part of the claimed design. The stipple or dot shading of the earphone-type electronic device with display as shown in the Figures represents a relatively soft and resilient portion thereof.
